SILENCER

Josef Laubacher, Wandsbek-Hamburg, Germany

Application August 10, 1934, Serial No. 739,338
In Germany October 9, 1933

7 Claims. (CL 137—160)

The invention concerns a silencer divided into several separate channels for the exhaust of combustion engines. The known silencers have the disadvantage, that they either attain an insufficient silencing effect or offer a very big resistance to the exhausting combustion gases. Further disadvantages consist in the fact, that they can be cleaned only with difficulty, or not at all of the soot or other residues of combustion which accumulate therein. Hereby the efficiency of the combustion engines is reduced. Moreover, these silencers are generally very troublesome in construction and expensive in producing them.

According to the invention, these disadvantages are removed in that, on the silencer, provided with several separate flow channels, a hollow constructed wall of the separate flow channels is filled with a sound-absorbing structural material and is partitioned intersected by one or several inlet-openings or channels in such a manner that one of said separate flow channels, having shortening its length, is led into another of the separate flow channels far from the entering place of the gases into the silencer.

The drawing schematically shows several examples of construction of the object of the invention:

Fig. 1 shows a form of construction of the silencer provided with sound-absorbing insertion in the outer walls of the spiral shaped inner partition wall in longitudinal section—partly in side elevation.

Fig. 2 shows the same form of construction in cross section on the line II—II of Fig. 1.

Fig. 3 shows the same form of construction in longitudinal section on the line III—III of Fig. 1.

Fig. 4 shows the same form of construction in view as seen from the exhaust side.

Fig. 5 shows another form of construction of the silencer with sound absorbing insertion in the spiral fitted inside.

Fig. 6 shows the same form of construction in cross section on the line VI—VI of Fig. 5.

1 is the outer casing of the silencer which is preferably constructed of drop form or cylindrical design with rounded ends and formed by two halves joined together by folding, welding, soldering etc. At the inlet place for the exhaust gas, the casing is provided with a tube shaped pipe-muff 2 which is detachably connected to the exhaust pipe of the combustion engine in question, by means of screwing, a bayonet lock, clamping clips or such means. Between the parallel side walls of the casing 1, a spirally shaped member is arranged, which, according to

Figs. 5 and 6 consist most suitably of twisted thin plate walls 3 and of a porous substance 4 for example of long shredded thin steel chips, asbestos or the like pressed in between these walls. The spiral members 3, 4 are held in position in the casing 1 by means of suitable screwing arrangement for example, angle pieces, grooves in the side walls or such like. The end 6 of the spiral member 3 protrudes knifelike into the exhaust gas inlet pipe 2 and, in consequence of its flexibility is adjustable here transversely to the direction of gas flow by means of an adjusting screw 7 outwardly protruding through the exhaust pipe 2. Owing to this adjustability of the end 6 of the spiral member 3, it is possible to alter the proportion of the parts of the gas current to each other which are separated from each other by the blade 6 and consequently the vibration load of the spiral member walls by means of the divided current. Moreover, the spiral member 3 can more or less be tensioned in this way. The plate walls 3 of the members 3, 4 may also be provided with holes in order to make them more flexible provided they are made somewhat stronger.

In the case of the construction example according to Figs. 1—4, the spiral member is constructed as a simple (an ordinary) wall without sound absorbing insertion 4. In this case, the side walls 8 of the spiral member 3 are constructed hollow and are filled up with sound absorbing insertion 10. In the last part of the passage of the passage channel formed by the spiral shaped member 3, outlet openings 11 are provided in the side walls 8 which are covered by cap shaped bonnets 12. The bonnets 12 are provided with exhaust openings 13 for the exhaust gases which are arranged at right angles to the outlet openings 11. The bonnets 12 are preferably constructed in a swallow-tail fashion. It is recommendable to affix one or both of them detachably to the casing 1. The casing 1 is provided with side-openings 14 of the size of the spiral member 3, and is provided with flanges 15 projecting outwardly over which the bonnets 12 overlap. In the case of rigid connection of bonnet 12 with the casing 1, the bonnets may be pressed out of the casing 1, or produced with same as one piece or be welded on to the same. The casing 1 may be constructed out of pressed plate strips or castings. The side flanges 15 as well as the bonnets 12 accommodate the side walls 8 with or without the sound absorbing insertion 10. In the beginning sphere of the by-channels formed by the blade 6, a guide wall 16

is built into the casing 1 parallel to the blade 8 by means of which the by-current is lead into the next following turning of the main passage channel in the flow direction of the exhaust gases.

The illustrated and described forms of construction may, with regards to shape, construction and arrangement of the single silencer parts, be subjected to numerous alterations without leaving the scope of the invention.

Having now particularly described and ascertained the nature of my said invention and in what manner the same is to be performed, I declare that what I claim is:—

15. 1. In a device of the class described, a silencer consisting of a single spiral main channel with an inlet opening at one end thereof and an outlet opening at the other end, and a shorter flow channel having its widest transverse dimension substantially the same as the widest transverse dimension of the main channel, opening into the main channel at a point intermediate the inlet and outlet of the main channel and having the same direction of flow as the main channel whereby the flow of the shorter channel causes in said main channel a reduction in pressure before the flow in said main channel reaches such point.
20. 2. In a device of the class described, a silencer consisting of a single spiral main channel with an inlet opening at one end thereof and an outlet opening at the other end, and a shorter flow channel having its widest transverse dimension substantially the same as the widest transverse dimension of the main channel opening into the main channel at a point intermediate the inlet and outlet of the main channel and having the same direction of flow as the main channel whereby the flow of the shorter channel causes in said main channel a reduction in pressure before the flow in said main channel reaches such point, parts of the walls of said main channel being of hollow construction and a sound absorbing substance in said hollow parts of said channel walls.
25. 3. In a device of the class described, a casing having parallel walls, a silencer in said casing consisting of a single spiral main channel with an inlet opening at one end thereof and an outlet at the other end, and a shorter flow channel having its widest transverse dimension substantially the same as the widest transverse dimension of the main channel opening into the main channel at a point intermediate the inlet and outlet of the main channel and having the same direction of flow as the main channel whereby the flow of the shorter channel causes in said main channel a reduction in pressure before the flow in said main channel reaches such point, a wall of said main channel being built in between the parallel walls of the casing, parts of the walls of said main channel being of hollow construction and a sound absorbing substance in said hollow parts of said channel walls.
30. 4. In a device of the class described, a casing having parallel walls, a silencer in the casing consisting of a single spiral main channel with an inlet opening at one end and an outlet opening at the other end, and a shorter flow channel having its widest transverse dimension substantially the same as the widest transverse dimension of the main channel opening into the main

channel at a point intermediate the inlet and outlet of the main channel and having the same direction of flow as the main channel whereby the flow into said main channel through said shorter channel causes a reduction in pressure before the flow in said main channel reaches said point, a wall of said main channel being built in between the parallel walls of the casing and laterally detachable therefrom, parts of the walls of said main channel being of hollow construction and a sound absorbing substance in said hollow parts of said channel walls.

5. In a device of the class described, a casing having parallel walls, a silencer in the casing and consisting of a single spiral main channel with an inlet opening at one end and an outlet opening at the other end, and a shorter flow channel having its widest transverse dimension substantially the same as the widest transverse dimension of the main channel opening into the main channel at a point intermediate the inlet and outlet of the main channel and having the same direction of flow as the main channel whereby the flow into said main channel through said shorter channel and outlet opening causes a reduction in pressure before the flow in said main channel reaches said point, a wall of said main channel being built in between the parallel walls of the casing, parts of the walls of said main channel being of hollow construction, a sound absorbing substance in said hollow parts of said channel walls and the two opposite side walls at the end of the main flow channel having at least one outlet opening therein.

6. In a device of the class described, a casing, 35 a silencer in the casing consisting of a single spiral main channel having an inlet and outlet at opposite ends with a second inlet intermediate the aforesaid inlet and outlet and a shorter flow channel opening into the main channel at the second inlet, the length of the main channel between the two inlets being greater than the length of the shorter channel, whereby the flow of the shorter channel causes a reduction in pressure in the main channel before the flow in the main channel reaches the second inlet, parts of the walls of said main channel being of hollow construction, and a sound absorbing substance in said hollow parts of said walls.

7. In a device of the class described, a casing, 50 a silencer in the casing consisting of a single spiral main channel having an inlet and outlet at opposite ends with a second inlet opening at an intermediate point, a shorter flow channel opening into the main channel at the intermediate inlet, the length of the main channel between the two inlets being greater than the length of the shorter channel, whereby the flow of the shorter channel into said main channel causes a reduction in pressure in said main channel before the flow in said main channel reaches the second inlet, parts of the walls of said main channel being of hollow construction, a sound absorbing substance in said hollow parts of said channel walls, and two opposite walls at the end of the spiral flow channel having at least one opening therein, cap shaped parts for covering said outlet openings in the side walls and said cap-shaped parts having outlet openings therein and being detachably arranged on the casing.

JOSEF LAUBACHER.
